FUEL METERING MEANS

Carl F. Schorn, Detroit, Mich., assignor to
George M. Holley and Earl Holley

Application January 10, 1947, Serial No. 721,305

12 Claims. (Cl. 123—25)

1

The object of this invention is to regulate the ratio of fuel to air in an internal combustion engine according to the speed of the engine and the density of the air entering the engine.

This case is an improvement over my Patent No. 2,397,984 which issued April 3, 1946. In this patent there is an inherent error due to the fact that the pressure drop across the apparatus is not constant and therefore a variable is thus introduced into the functioning of the apparatus so that the apparatus can not compensate 100%. In this present invention the drop across the device is maintained substantially constant.

The figure shows diagrammatically the preferred form of my invention.

In the figure 10 is the fuel entrance, 11 is the fuel outlet. 12 is the shaft which is driven at engine speed or at a fraction thereof. 13 is the main fuel pump which supplies the fuel for the engine and this pump is driven at engine speed or at a fraction thereof. 14 is an auxiliary recirculating positive displacement metering fuel pump driven by the shaft 12 which creates pressures proportional to the square of the engine revolutions per minute and thus forms part of the control mechanism regulating fuel flow. This pump 14 draws fuel from the chamber 29, which chamber draws fuel through a restriction 23, past a contoured needle 25, from a chamber 24. Fuel is thus recirculated in a closed circuit to establish a pressure difference responsive to speed. 15 is a connection which admits the intake manifold pressure from the engine side of a supercharger 158 and imposes supercharger pressure in the chamber 49 which contains a flexible metal capsule assembly. This capsule assembly consists of evacuated elements 18. An exhaust passage 16 communicates to the chamber below the diaphragm so as to impose the exhaust pressure on the diaphragm 17. The upper side of the diaphragm 17 is subjected to the manifold air pressure in the chamber 49. The diaphragm 17 thus responds to the difference between supercharger and exhaust pressures. These two elements, the pressure created by the engine driven pump 14, and the pressure responsive elements 17 and 18, constitute the pressure elements of the speed density combination which is the characteristic feature of this invention.

Valve 19 is the fuel metering device which is connected to the evacuated element 18 and to the diaphragm 17. The valve 19 is located in a fuel passage 20 and controls the fuel flow from the passage 20 to the fuel outlet 21. The passage through the center of the valve 19 permits the

2

pressure to chamber 49 to be applied to the upper end of the valve 19.

The positive displacement pump 14 creates a pressure differential across the restriction between the orifice 23 and the contour needle 25. This pressure drop varies directly with the square of the revolutions per minute of the engine by circulating fuel from the fuel pump 13, through the metering pump 14, to chamber 24, past the restriction 23—25, back into the fuel inlet 56. The fuel inlet 56 is the fuel outlet of the pump 13. This fuel pump 13 has a pressure regulating valve 58, loaded with a spring 60, connected through a pipe 63, through the shut-off valve 64 to the fuel outlet passage 34, through the passage 37 to the fuel valve 70 which controls the flow of fuel through the passage 11 to the center of the supercharger spinner, not shown, leading to the supercharger 158.

20 The movable needle 25 is responsive to a temperature device 26, which is located in a chamber 170 through which compressed air flows from supercharger 158 through the chamber 49, through the pipe 171 and escapes to the atmosphere from the chamber 170, and is adapted to control the area of the restriction 23—25.

25 The chamber 31, to the right of diaphragm 30, is connected through passage 47 to the fuel inlet 56. The area of the fuel screen 68 is such that the pressure drop there-through is negligible as the quantity bypassed past the variable orifice 23—25 is relatively small.

30 The chamber 31, to the right of diaphragm 30, communicates through passage 47 to the fuel inlet 56. The area of the fuel screen 68 is such that the pressure drop there-through is negligible as the quantity bypassed past the variable orifice 23—25 is relatively small.

35 The chamber 31, to the right of diaphragm 30, communicates through passage 47 to the fuel inlet 56. The area of the fuel screen 68 is such that the pressure drop there-through is negligible as the quantity bypassed past the variable orifice 23—25 is relatively small.

40 The chamber 31, to the right of diaphragm 30, is connected to the shaft 32. Connected to the diaphragm 30 is the balanced pressure control valve 33. When the engine speed causes an increase in the pressure drop across diaphragm 27, the shaft 32 and diaphragm 30 move to the right and valve 33 moves to the left to increase the fuel discharge opening from chamber 21 to outlet passage 34. This causes an increase in the pressure drop across the valve 19 and thus across the diaphragm 30.

45 The chamber 31, to the right of diaphragm 30, is connected to the shaft 32. Connected to the diaphragm 30 is the balanced pressure control valve 33. When the engine speed causes an increase in the pressure drop across diaphragm 27, the shaft 32 and diaphragm 30 move to the right and valve 33 moves to the left to increase the fuel discharge opening from chamber 21 to outlet passage 34. This causes an increase in the pressure drop across the valve 19 and thus across the diaphragm 30.

50 Fuel in passage 34 lowers the diaphragm 35 and fuel discharges to the engine through outlet 11. Diaphragm 35 is loaded with the spring 36 and the inlet fuel pressure which is supplied through passage 62, past the shut-off valve 64 and to a fuel tank 72 through a passage 65.

There is then maintained an adequate pressure in the passage 34. The tank 72 forms the low pressure outlet from the passage 65 and is open to the atmosphere. The main fuel entrance 10 is also at a low pressure similar to that existing in the fuel tank 72.

A fuel venturi 38 in the passage 20, leading to the valve 19 creates a pressure difference which responds to the flow of fuel. The pressure of the fuel entering the venturi 38 is applied to the left hand side of the diaphragm 39 through passage 74 and the decreased pressure in the throat of the venturi 38 is applied to the right hand side of a diaphragm 39 through the passage 40. Diaphragm 39 is supported by spring 41 and supports the tapered needle 42, which controls the supply of the extra fuel needed for high power, especially in an air-cooled engine where extra fuel is required to prevent the engine from overheating. This fuel flows along the passage 76 and past the diaphragm 78, and then around the projection at the end of the tapered needle 42. The end of the projection of the needle 42 is provided with a taper 80 which controls the flow of water from the water entrance 82, past the valve 84 mounted on the diaphragm 78, through the passage 86, past the needle 80, into the passage 34. The valve seat 84 on the diaphragm 78 responds to pressure in the water inlet 82 and shuts off the flow of fuel through the fuel passage 76 so that the diaphragm 39 controls the admission of extra fuel to prevent knock and alternatively controls the supply of water or some equivalent fluid to prevent knock.

The valve 46, shown in the upper left hand corner, is the fuel mixture control valve and is shown in the full rich position. In this full rich position the passage 65 is connected through the valve 46 to the chamber 43, above the diaphragm 44, which diaphragm 44 is connected to the movable restriction 23. Adjustable spring 48 pushes the diaphragm 44 downwardly. The fuel entrance pressure in passage 56 is transmitted through the passage 88 to the under side of the diaphragm 44. There is a smaller diaphragm 90 also connected to the movable restriction 23 and the lower side of this diaphragm 90 is subjected to the pressure in the chamber 24. The upper side of the diaphragm 90 is subjected to the pressure in the passage 88 which is equal to the pressure in the fuel entrance 56. An adjustable stationary stop 94 is adapted to engage with an adjustable movable stop 92 carried on the end of the restriction 23. The downward movement of the movable restriction 23 in response to the spring 48 is brought to a stop when the movable stop 92 encounters the adjustable stop 94. The upward movement of the movable restriction 23 is adjusted by the stationary adjustable stop 96.

The shut-off valve 64 is rotated when it is desired to shut the mechanism down and in the position shown it is in the operating position.

When it is desired to transfer from full rich to cruising lean the valve 46 is rotated anti-clockwise by means of the lever 47 so as to place the chamber 43 in communication with the throat of the fuel venturi 48 through the passage 110. This is shown by the broken lines in the valve 46. This reduces the flow of fuel as it reduces the pressure drop acting on the diaphragm 27 and thereby reduces the quantity of fuel flow past the valve 23.

Idle system

In the idle system the diaphragm 98, shown

immediately below the shut-off valve 64, carries the idle needle 100 and the two opposing springs 102 and 104 maintain the needle 100 in the neutral position. Passage 106 admits the pressure in the chamber 24, to the left hand side of the diaphragm 27. Passage 106 is connected to the right hand side of the diaphragm 98. The passage 108 is connected to a chamber at the same pressure as the pressure in passage 88 and thus imposes the pressure in the fuel entrance 56 on the left hand side of the diaphragm 98 so that at low speed, when idling, the valve 100 is open and when not idling valve 100 is closed. The spring 102 is more powerful than spring 104. The fuel then flows through 108 to the right, past the needle 100, up the passage 34, past the valve 70 to the passage 11. When the speed of the engine increases, valve 100 shuts because the pressure in chamber 24 rises and hence the pressure in passage 106 rises. When the fuel pump 14 is operating at a low speed, valve 136 is seated so as to prevent fuel flowing from the fuel pump 14 to the fuel chamber 24. The spring 140 seats the valve 136, the restriction 138 then delivers a little fuel to the passage 88 and returns the fuel to the fuel entrance 56. Hence, during the slow speed (idling) operation the fuel metering is performed by the idle valve 100.

Accelerating system

Cam 112 engages with a roller 114 and is driven by the shaft 116. Shaft 116 and cam 112 are rotated anti-clockwise when the air throttle 157 is open. This is accomplished by suitable link motion. The diaphragm 120, connected to the roller 114, is the left hand wall of the chamber 122 which forms the acceleration fuel pump. Fuel is admitted past the restriction 124 which is connected to the passage 88, which is connected to the fuel entrance 56. Fuel is discharged from the chamber 122 whenever the throttle is closed and fuel flows past the valve 126 which is seated by means of the spring 128. Whenever the throttle is open chamber 122 is enlarged and the diaphragm 130 moves to the left and carries with it the valve 132. Fuel is thus admitted from the passage 88 past the acceleration restriction 134 to the main fuel passage 34.

Operation

When the mixture control valve 46 is in the position shown, that is, in the full rich position, fuel entering at 10 is raised in pressure by the pumps 13 and 14 and acts on diaphragm 27, which pushes rod 32 to the right and opens valve 33, this lets fuel for the engine into passage 34 and past the diaphragm 35 to the fuel outlet 11. The pressure drop across the restriction 23-25 and, therefore, the drop across diaphragm 27 and 30 and the valve 19 varies (for a given temperature) as the square of the engine speed. The flow past the valve 19 at any given opening will vary as the square root of the drop across the valve. Therefore, the flow varies directly with engine speed. The size of the opening past valve 19 is controlled by the intake manifold pressure in chamber 49. Therefore, the flow into the engine varies with engine speed and manifold air pressure.

Assuming that this device and the power plant it controls are mounted upon a plane, then as the plane ascends, the pressure below the diaphragm 17 falls and thereby causes a relative decrease in the capsule height at a given manifold air pressure. This causes the valve 19 to further

move to increase the opening between passages 20 and 21 and, therefore, the fuel flow to the engine is increased. The increase in fuel flow compensates for the increase in air flow into the engine due to the fall in back pressure (at any given engine speed and manifold pressure) caused by the decrease in pressure on the exhaust side of the engine. An increase in intake manifold temperature causes an increase in the size of the opening through restriction 23 and, thereby, the metering head across valve 19 is reduced for any given speed. This change in metering head compensates for the temperature variations in manifold temperature reducing the fuel flow as the temperature increases and decreasing the air density.

When increased engine speed and manifold pressure, the increase in the fuel flow through the fuel venturi 38 causes the pressure drop across diaphragm 39 to increase until the strength of the spring 41 is overcome and additional fuel passes valve 42 and is admitted to the engine.

To operate at better economy, the valve 46 is manually rotated anti-clockwise into the cruise lean position and the drop across the restriction 23 is lowered because the pressure existing in chamber 43 is increased as the passage 110 now communicates with the chamber 43 and with the pressure in the fuel entrance 56. After a certain fuel flow is reached in the venturi 38 there is a slight decrease in pressure in the chamber 43. This decrease in pressure in the chamber 43 has a tendency to make the mixture ratio richer. Just as the ratio of the valve 46 places the low pressure passage 65 in communication with the chamber 43 it also has a tendency to make the fuel ratio richer. This causes a lower metering head across the metering valve 19 and therefore a decreased fuel flow at any given engine speed.

The device shown has been divorced from the air control means of the engine and its operation is quite independent of the air flow and of the density of the air entering the engine, being controlled simply by the revolutions per minute, the temperature of the air entering the engine cylinder and the intake manifold pressure, which are the controlling factors in determining its desired fuel supply.

What I claim is:

1. A fuel metering device for an internal combustion engine, said device having a constant pressure discharge valve, an engine driven fuel supply pump discharging into the fuel inlet of said device, pump pressure regulating means for said pump adapted to maintain a constant pressure drop between the fuel inlet to said device and the pressure side of said constant pressure discharge valve, a fuel measuring valve therein, a restricted passage, an engine-driven ancillary pump adapted to displace fuel in proportion to the engine revolutions per minute and connected to said restricted passage so as to pump fuel through said restricted passage, a moving wall, two chambers located one on each side of said wall, one chamber being connected to the high pressure side of the said ancillary pump and on the other being connected to the low pressure side of said pump, a second moving wall connected with the first moving wall, two chambers located one on each side of said second wall, one of said last mentioned chambers being connected to the pressure on the upstream side of the fuel measuring valve and the other side thereof being connected to the downstream side of the fuel measuring valve, a second valve located in the fuel

passage downstream from the fuel measuring valve and adapted to be opened and closed by the movement of said moving walls so as to control the pressure difference across said measuring valve, to balance the pressure created by said ancillary pump, a fuel outlet for said second valve, means responsive to the supercharger pressure for opening and closing said fuel measuring valve.

2. A device as set forth in claim 1, in which there is a second fuel passage and a second fuel measuring valve located in parallel with the first fuel measuring valve and first fuel passage, means responsive to the rate of fuel flow through said first fuel passage and first measuring valve for opening said second fuel measuring valve when the flow through the first passage exceeds a predetermined value.

3. A device as set forth in claim 1, in which there is an idling fuel passage and measuring valve located in parallel with the first fuel measuring valve and adapted to supply the fuel required for idling, means responsive to the engine-driven ancillary pump for closing said idling fuel measuring valve as the engine speed is increased above the idle speed.

4. A device as set forth in claim 1 in which there is a water entrance, a water passage connecting said entrance to fuel outlet, an automatic valve in said water passage controlling the water flow, means responsive to the rate of fuel flow through said fuel passage past said fuel measuring valve for opening said water valve.

5. A device as set forth in claim 1, in which there is a second fuel passage and a second fuel measuring valve means located in parallel with the first fuel measuring valve and first fuel passage, means responsive to the rate of fuel flow through said first passage and first fuel measuring valve for opening said second fuel measuring valve when the flow through the first fuel measuring valve and passage exceeds a predetermined value, a water entrance, a water passage connecting with said fuel outlet and in parallel with said first fuel measuring valve, means responsive to the rate of fuel flow through said first fuel measuring valve and passage to admit water to the fuel outlet, means responsive to the pressure of the water for restricting the fuel flow through said second fuel measuring valve.

6. A device as set forth in claim 1, in which there is a temperature responsive means to modify the action of said pump, whereby at high temperatures, the pressure generated by the engine-driven ancillary pump for any given revolutions per minute will be lower than at low temperature.

7. A device as set forth in claim 1 in which the means responsive to the supercharger pressure is modified by means responsive to the difference between the supercharger pressure and the pressure of the exhaust.

8. A device as set forth in claim 1 in which the ancillary pump adapted to displace fuel in proportion to the revolutions per minute is provided with a variable restriction formed between two elements consisting of a movable needle and a movable restriction, temperature responsive means for moving one element, a manually operated means for moving the other element into one of two positions so that there is a power mixture range and a cruising lean range manually selectable but which at the same time is subject to control by the temperature responsive means.

9. A device as set forth in claim 1 in which there is a spring loaded poppet valve adapted to

modify the relationship between the pressure differential across the restricted passage and the fuel flow through the ancillary pump in response to the speed of the engine.

10. A device as set forth in claim 1 in which the ancillary pump adapted to displace fuel in proportion to the revolutions per minute of the engine is provided with a variable restriction, the flow through which creates a pressure drop across the said restriction, and manually operated means for selecting the maximum and minimum areas of said variable restriction.

11. A device as set forth in claim 1 in which the ancillary pump adapted to displace fuel in proportion to the revolutions per minute is provided with a variable restriction, the flow through which creates a pressure drop across said restriction, manually operated means for selecting the maximum and minimum areas of said variable restriction, and means responsive to the flow of fuel past said fuel measuring valve for automatically restoring the variable restriction to its minimum position whenever the flow exceeds a predetermined value to prevent the operation at high power output with minimum fuel air ratios.

12. A fuel metering device for an internal combustion engine, said device having a constant pressure discharge valve, an engine-driven fuel supply pump discharging into the fuel entrance to said device, pump pressure regulating means for said pump adapted to maintain a constant pressure drop between the fuel inlet to said device and the pressure side of said constant pressure discharge valve, a fuel passage from said entrance, a fuel measuring valve therein in free communication with said fuel pump, a restricted

passage, an ancillary engine-driven pump adapted to displace fuel in proportion to the engine revolutions per minute and connected to said restricted passage so as to pump fuel through said restricted passage, a moving wall, two chambers located one on each side of said wall, one chamber being connected to the high pressure side of said ancillary pump and on the other being connected to the low pressure side of said ancillary pump, a second moving wall connected with the first moving wall, two chambers located one on each side of said second wall, one of said last mentioned chambers being connected to the pressure on the upstream side of the fuel measuring valve and the other chamber located on the other side thereof being connected to the downstream side of the fuel measuring valve, a second valve located in the fuel passage downstream from the fuel measuring valve and adapted to be opened and closed by the movement of said moving walls so as to control the pressure difference across said measuring valve, to balance the pressure created by said second pump, a fuel outlet for said second valve, and means responsive to the manifold air pressure for opening and closing said fuel measuring valve.
